CIGAR AND CIGARETTE LIGHTER

Edgar M. Soreng, Chicago, Ill., assignor to
Soreng-Manegold Company, Chicago, Ill., a
corporation of Illinois

Application June 9, 1933, Serial No. 674,998

14 Claims. (Cl. 219—32)

This invention relates to certain new and useful improvements in electrical cigar and cigarette lighters and has as a general object to provide an improved lighter of the type having a loose conveniently handled igniter unit capable of being passed around as an ordinary pocket lighter after being electrically energized or heated by temporary connection with a pair of electrically live terminals.

More specifically, it is an object of this invention to provide an improved igniter unit of the character described, which will retain its heat longer and by reason of its novel construction, insures a quicker transfer of heat to the cigar or cigarette to be lighted.

Another object of this invention is to provide an improved manner of connecting the lighter unit with a source of electrical energy.

A further object of this invention is to provide a neat compact combination of an igniter unit of the nature defined and a supporting receptacle wherein the igniter unit, when not in use, is supported in a position from which it is only necessary to depress the same slightly to effect its connection with a source of electrical energy.

With the above and other objects in view which will appear as the description proceeds, my invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view of the igniter unit;

Figure 2 is a side elevation with parts broken away and in section of the supporting receptacle for the igniter unit;

Figure 3 is a cross section view through Figure 2 on the plane of the line 3—3;

Figure 4 is a plan view of the igniter unit showing more clearly the arrangement of the heater element; and

Figure 5 is an enlarged section view taken through Figure 4 on the plane of the line 5—5.

Referring now more particularly to the accompanying drawing in which like numerals indicate like parts throughout the several views, the nu-

meral 4 designates generally the base or body of an igniter unit having a handle portion 5 and a heating element 6, which is preferably a coil of resistance wire adapted to be brought to a state of incandescence. For this purpose, the resistance wire is adapted to be connected with a source of electrical energy, but the connection is only temporary and is effected without wires or other permanent electrical connections to the igniter unit in a manner to be later described. Consequently, the igniter unit is free and may be readily passed around or used as an ordinary pocket lighter as long as the heater coil retains sufficient heat.

The base or body 4 of the igniter unit is formed of a flat piece of insulating material with its end portion 7 opposite the handle part 5 cut away as at 8 to define a chamber within which the resistance element 6 is disposed. The opposite sides of this chamber are closed by thin walls 9 formed of mica or similar electrically insulating material.

The walls 9 are retained in place by metal side frames 10 secured to opposite sides of the end portion 7. These side frames 10 have lateral flanges 11 on three sides thereof to overlie the edges of the mica walls 9, and the adjacent outer walls of the body portion 7. The fourth sides of the frames 10 have no lateral flanges and as best shown in Figure 4, project into a groove 12 completely encircling the end portion 7 of the supporting body at its juncture with the handle part 5. The adjacent ends of the lateral flanges 11 also project into this groove. The side frames 10 are thus securely retained against flatwise movement away from the body end portion 7.

Endwise movement of the side frame 10 is precluded by rivets 13, which are received in holes 14 through corner bosses 15 formed as an integral part of the body end portion 7, and each of which passes through a hole formed in one of the side frames.

Inasmuch as the side frames are electrically disconnected, and as each rivet 13 contacts but one frame, the frames afford external terminals 45 for electrically connecting the resistance wire 6, which has its ends attached to the rivets 13, with a source of electrical energy.

The specific manner of making this electrical connection between the resistance coil ends and the rivets is, of course, immaterial, but if desired, it may be made in the manner illustrated in Figure 4. As here shown, the ends of the resistance wire are looped about and preferably soldered to the rivets between the insulating

body and metal washers 16 positioned inwardly of the mica walls 9.

As best shown in Figure 3, the resistance coil 6 is wound about an inner sheet of mica or other suitable insulating material 17 and arranged in a zig-zag fashion so that a plurality of lengths of the coil are located at each side of the unit. The diameter of the coil is such that it contacts directly with both side walls 9, thus insuring rapid heat transfer by conduction to a cigar or cigarette held against either wall 9. To further increase the rapidity of the heat transfer, the side walls 9 are perforated as at 18.

The heater element or wire coil of the igniter unit is connectable with a source of electrical energy by engaging the two side frames 19, which serve as its terminals with live terminals 19 and 20. The terminals 19 and 20 are mounted in a supporting housing indicated generally by the numeral 21, and are connectable with a source of electrical energy through conductor wires 22.

The supporting housing or casing 21 not only forms an enclosure for the terminals, but also provides a convenient receptacle for the igniter unit when the same is not in use. It comprises a shell of insulating material 23 of any desired design or configuration and ornamented on its outer walls if desired. Closing the open top of the shell 23 is a top plate 24 having a rectangular opening 25 through which the igniter unit is inserted, the opening being of such size as to hold the igniter unit against any but endwise movement.

The top plate 24 supports a box-like inner housing 26 also formed of insulating material and on the bottom of which the terminals 19 and 20 are mounted, one near each side wall of the housing 26, see Figure 2. The interior of the box-like inner housing 26 is substantially a continuation of the opening 25 in the top plate 24 and is of such depth that when the igniter unit is disposed therein, only its ornamented handle part 5 projects from the receptacle.

When disposed within the receptacle, the unit is supported on the terminal 20, which projects above the terminal 19. Consequently, the terminal 19 is not engaged by the igniter unit and no current flows through its heater coil.

To engage the igniter unit with the terminal 19, it is merely necessary to press the same down into the receptacle, the terminals and particularly the terminal 20, being formed of spring metal to permit such depression of the igniter unit. As before stated, the igniter unit is held against all sidewise or twisting movement when disposed in the receptacle and as the terminals are located near opposite sides of the chamber into which the unit is inserted, depression of the unit into the receptacle results in the engagement of one terminal with each of the metal frames 19 of the igniter unit, thus electrically bridging the terminals 19 and 20 through the resistance coil.

The terminals 19 and 20 may be formed by the outer upturned ends of angularly shaped spring metal members, the opposite ends of which are riveted to the under surface of the bottom wall of the inner housing as at 27 with the terminals proper projecting upwardly through apertures 28. The rivets 27 also provide contact terminals to which the conductors 22 are soldered, the conductors being brought into recesses 29 in the bottom wall of the inner housing which are closed by a guard plate 30 secured

to the bottom wall of the inner housing by a rivet 31.

As hereinbefore noted, the igniter unit when not in use is disposed in the receptacle and rests on the longer terminal 20 out of contact with the terminal 19. When it is desired to use the igniter unit, it is first depressed so that contact is established between the terminal 19 and its respective side wall 19, whereupon current flows through the resistance coil 6 causing it to heat up. The igniter unit is then removed from the receptacle and as the resistance coil retains its heat for a substantial period of time, the unit may be used as any ordinary electrical pocket lighter and being unencumbered by conductor 15 wires, may be passed around from one user to another.

What I claim is my invention is:

1. An igniter of the character described, comprising an easily handled relatively flat member 20 of insulating material having an opening entirely therethrough to define a chamber, a coiled electrical resistance wire arranged in a flat plane within said chamber, walls closing the opposite sides of said chamber, said walls being formed of a 25 dielectric material and lying directly adjacent the coiled electrical resistance wire to afford rapid heat transfer by conduction to an object engaged with either wall, and means on the exterior of said supporting body electrically connected with the 30 ends of the coiled resistance wire and adapted to be held against live electric terminals to cause current to flow through said coiled resistance wire.

2. An igniter of the character described, comprising a relatively flat member having an opening 35 transversely therethrough to define a heater chamber, a length of electrical resistance wire disposed within said chamber, dielectric walls closing the opposite sides of said chamber and lying in close proximity to said resistance wire to rapidly conduct heat from said resistance wire to an object held against either wall, a metal frame engaged over each of said walls to hold the same in place, and means to connect one end of said length of resistance wire with one frame and the other 40 end with the other frame, whereby the engagement of said frames with two spaced live terminals of an electrical circuit causes current to flow through said length of resistance wire.

3. An igniter of the character described comprising, a relatively flat supporting body of insulating material having an opening transversely therethrough to define a chamber, a heating unit within said chamber comprising a coil of resistance wire mounted on a flat insulating support 55 so that a plurality of lengths of said coil are disposed on each side of said insulating support, dielectric walls closing the opposite sides of said chamber and retaining said heating unit in place, said walls being in close proximity to the coil of 60 resistance wire to afford rapid heat transfer to an article held against either of said walls, a metal frame overlying each of said dielectric walls, and means to electrically connect one of said metal frames with each end of said coil of resistance wire, whereby engagement of said metal frames with live electric terminals connects the coil in a circuit to cause the same to be heated.

4. An igniter unit of the character described, comprising a flat member of insulating material 70 having a transverse opening therethrough and a grooved shoulder extending transversely thereabout, heater means within said chamber comprising a flat sheet of insulating material fitted within said chamber, a coil of electrical resistance wire 75

wound on said flat sheet to have portions thereof lying on opposite sides of the sheet, dielectric walls closing the opposite sides of said chamber to retain the heater means in place and lying in close proximity to the coil of resistance wire, a metal frame engaged over each of said dielectric walls, the inner ends of said frames being received in said groove whereby said frames are held against flatwise movement away from the opposite sides 5 of said flat member, securing means to hold said frames against endwise shifting, one of said securing means passing through and electrically contacting one frame and the other securing means passing through and electrically contacting 10 the other frame, and the ends of said coiled resistance wire being electrically connected with said securing means, whereby the metal frames afford external terminals for the resistance coil to enable the coil to be connected with a source 15 of electrical energy.

5. An igniter of the character described comprising a handle member, an electrical resistance element in the form of a length of coiled wire, a flat supporting member about which the resistance element is wound with portions thereof on opposite sides of the supporting member, means to mount said supporting member from the handle member with the resistance element portions at opposite sides thereof accessible for use, and means to connect the resistance element with a source of electrical energy to cause the resistance element to heat up.

6. An igniter of the character described comprising, a member having an opening transversely therethrough to define a heater chamber, a length of electrical resistance wire disposed within said chamber, dielectric walls closing the opposite sides of said chamber and lying in close proximity to said resistance wire to rapidly conduct heat from said resistance wire to an object held against either wall, a metal frame engaged over each of said walls to hold the same in place, and means to connect one end of said length of resistance wire with one frame and the other end with the other frame, whereby the engagement of said frames with two spaced live terminals of an electrical circuit causes current to flow through said length of resistance wire.

7. An igniter of the character described, comprising a body member having a chamber to receive a heater element, a length of electrical resistance wire disposed in said chamber, a dielectric wall closing one side of the chamber and lying in close proximity to said resistance wire to rapidly conduct heat from said resistance wire to an object held against said dielectric wall, a pair of spaced metal elements mounted on said body member, one of said metal elements being disposed over the dielectric wall to hold said wall to the body member over the chamber therein, and said metal element having an opening to afford access to the dielectric wall, and means to connect the ends of the resistance wire with the metal elements, whereby the engagement of said metal elements with two spaced live terminals of an electric circuit causes current to flow through said length of resistance wire.

8. An igniter of the character described comprising, a handle member, an electrical resistance element in the form of a coiled wire, means carried by the handle member to support the resistance element in substantially a flat plane with both its sides accessible for use, and metal frames disposed about the edges of the resistance element to protect the edges of the element while

leaving its sides free and accessible, said metal frames being fixed to the handle member in electrically spaced relationship and each being connected to one end of the resistance element, whereby said frames afford terminals for the ends of the resistance element engageable with the live terminals of an electrical circuit to connect the resistance element with the circuit to cause the resistance element to heat up.

9. A cigar and cigarette lighter unit comprising, a handle member, an electrical resistance element in the form of a coiled wire, a support carried by the handle member and on which the resistance element is wound with portions thereof in substantially two parallel flat planes both of which are accessible for use, and terminals for the ends of the resistance element carried by the handle member and engageable with live terminals for connecting the resistance element with a source of electrical energy to cause the resistance element to heat up, said terminals having parts disposed along the edges of the resistance element to protect said edges of the resistance element.

10. An igniter of the character described comprising, a handle member, a pair of overlying but electrically separated metal frames carried by the handle member to define an enclosure open at two opposite sides, an electrical resistance element in said enclosure with both its sides accessible for use through the open sides of the enclosure, and means to electrically connect the ends of the resistance element with the metal frames so that said frames provide terminals for the resistance element engageable with live terminals of an electric circuit to connect the resistance element with said circuit and cause the resistance element to heat up.

11. An igniter of the character described comprising, a handle member, a pair of overlying but electrically separated metal frames carried by the handle member to define a substantially flat enclosure, dielectric walls closing the openings defined by said frames and forming sides for said substantially flat enclosure, an electrical resistance element in said enclosure between said dielectric walls and in close proximity thereto, whereby heat from the electrical resistance element is rapidly conducted to a cigar or cigarette held against either of said dielectric walls, and means to electrically connect the ends of the resistance element with the metal frames so that said frames provide terminals for the resistance element engageable with live terminals of an electric circuit to connect the resistance element with the circuit and cause the resistance element to heat up.

12. An igniter of the character described comprising, a handle member of insulating material, a pair of overlying but electrically separated metal frames carried by and projected from one end portion of the handle member to define a substantially flat heater enclosure at said end of the handle member, an electrical resistance element in the form of a length of coiled wire, means within said enclosure to support said resistance element in a substantially flat formation between the metal frames with both its sides accessible for use through the openings defined by the frames, and means to connect one of said frames to each end of the resistance element whereby said frames provide terminals for the resistance element engageable with live contacts for connecting the resistance element in an electric circuit to cause the same to heat up.

13. An igniter unit of the character described comprising, a pair of overlying but electrically separated metal frames defining a substantially flat enclosure, means to maintain said frames properly spaced apart, an electric resistance element in the form of a length of coiled wire, means within said enclosure defined by the frames to support said resistance element in a substantially flat formation between the frames 5 with its opposite sides accessible for use through the openings of the frames, means to connect each frame to one end of the resistance element whereby the frames provide terminals for the resistance element engageable with electrically 10 live contacts to enable the passage of current through the resistance element, and an insulating handle to enable handling of said igniter and facilitate the engagement of the frames with the electrically live contacts.
- 15 14. An igniter device comprising, a receptacle adapted to rest on a supporting surface and having an open topped well, a flat insulating wall 20

extending across the bottom of the well, a pair of angularly shaped electric contacts, each having one leg fixed to the bottom external surface of the insulating wall and its other leg projecting upwardly through an opening in said insulating wall, the upwardly projecting leg of one contact extending above that of the other and being depressible, an igniter unit comprising, a handle member, a pair of metal frames carried by the handle member in electrically spaced relationship but overlying each other to define a heater enclosure, a heater element disposed in said enclosure with its ends fixed to the metal frames whereby the metal frames form terminals for the heater element, and said igniter unit 15 being insertable into the well of the receptacle so that one of said frames engages the depressible contact and the other frame engages the other of said contacts upon forced depression of the igniter unit into the well.
